UNITED STATES PATENT OFFICE.

GEORGE T. JACOCKS, OF POTTSTOWN, PENNSYLVANIA.

FORGING-DIE.

1,213,878.

Specification of Letters Patent. Patented Jan. 30, 1917.

Application filed May 11, 1916. Serial No. 96,793.

To all whom it may concern:

Be it known that I, GEORGE T. JACOCKS, a citizen of the United States, residing at Pottstown, in the county of Montgomery and State of Pennsylvania, have invented certain new and useful Improvements in Forging-Dies, of which the following is a specification, reference being had therein to the accompanying drawing.

10 This invention relates to improvements in dies for forging metals, one object of the invention being the provision of a punch or male member which fits tightly into the cavity of the female member and acts upon the 15 material to be forged, the male member being provided with one or more surplus metal receiving grooves in the face thereof so that the forged piece may be made accurately to the dimensions of the die cavity, 20 one face thereof being completed entirely, while the opposite face is provided with one or more surplus metal projections which are removed by a planer or other machine.

A further object of this invention is the 25 provision of a die of this character which can be operated by unskilled labor to produce an accurate forging that is not fractured, due to the compression placed thereupon when a surplus amount of metal is 30 placed in the die cavity.

In the accompanying drawings:—Figure 1 is a sectional view through the die members, showing the forging in place and the parts in forming position. Fig. 2 is a sectional view through the lower end of the 35 male die member. Fig. 3 is a bottom plan view thereof. Fig. 4 is a plan view of the upper face of a forging with the surplus metal removed.

40 Referring to the drawings, the numeral 5 designates the female die constructed as is usual with a knock out, and having the forging receiving cavity 6, for the forging 7. The present forging shown clearly in plan 45 in Fig. 4, and which is the time train carrying member of a brass time fuse, is merely indicative of any form of forging that may be made with a die employing the principles of the present invention.

50 The male punch 8, is here shown composed of the outer member 13, the intermediate member 14, and the inner or center member 15, all of which are telescoped, and are adapted to be operated independently,

the member 15 being pressed downwardly 55 first, the annular member 14 next, and the outer member 13 last.

The member 15 adjacent its outer edge is provided with the flash pocket or groove 9, which is here shown circular, while the 60 member 13 upon its inner edge is provided with the shallower flash pocket or groove 10. The metal engaging end 11 of the member 13 is rounded, and is crescent shape to form the crescent shape time train holding de- 65 pression or groove in the forging 7.

In operation, the cavity 6 is filled to the proper depth with the metal either cold or semi-molten for the forging 7. The member 15 is then moved down to its proper seat 70 to prevent the metal from flashing circumferentially, being next followed by the member 14, and finally by the outer member 13. Thus the surplus metal is crowded into the two grooves 9 and 10, and the forging 75 is formed without crystallization, and not as is the case in the usual method of making forged articles by striking and crowding or compressing the metal under unnatural strains. 80

With this construction of forging die, the various objections to the dies now in use are removed, and a more perfect forging is the result, in that metal parts are made to a size of very close dimensions and without 85 pouring the exact amount of metal in the female die, the surplus metal which is received upon the male die side thereof being shaved off in a lathe or metal planer. 90

What I claim as new is:—

The herein described forging die, including a female die having a forging receiving cavity, and a male die fitting snugly in the cavity to prevent flashing from the circumferential edge of the male die, said male 95 die having a groove, or grooves, formed upon the forging engaging face thereof for receiving the surplus metal of the forging that is to be removed to form a finished forging, and a movable forging engaging member carried by the male die and forming a part thereof, said movable forging engaging member acting to spread the metal in the cavity and cause the surplus to enter the groove or grooves. 100

105 In testimony whereof I affix my signature.

GEORGE T. JACOCKS.
